US0D1102476S

(12) **United States Design Patent** (10) Patent No.: **US D1,102,476 S**
(45) Date of Patent: ** *Nov. 18, 2025

(54) **DISPLAY SCREEN OR PORTION THEREOF
WITH GRAPHICAL USER INTERFACE**

(71) Applicant: **Katherine M. Sauer**, Evansville, IN (US)

(72) Inventor: **Katherine M. Sauer**, Evansville, IN (US)

(*) Notice: This patent is subject to a terminal disclaimer.

(**) Term: **15 Years**

(21) Appl. No.: **29/906,292**

(22) Filed: **Nov. 2, 2023**

(51) LOC (15) Cl. **14-04**

(52) U.S. Cl. USPC **D14/485**

CLAIM

The ornamental design for a display screen or portion thereof with graphical user interface, as shown and described.

DESCRIPTION

The FIGURE is a front view of a display screen or portion thereof with graphical user interface, showing my new design.

The broken lines around the FIGURE show a display screen or portion thereof and form no part of the claimed design.

1 Claim, 1 Drawing Sheet
